CLAIM

The ornamental design for a molded flange for use with a filter respirator, as shown and described.

DESCRIPTION

FIG. 1 is a front perspective view of a molded flange for use with a filter respirator according to my new design,

FIG. 2 is a rear perspective view thereof,

FIG. 3 is a back view thereof,

FIG. 4 is a front view thereof,

FIG. 5 is a top plan view thereof,

FIG. 6 is a bottom plan view thereof,

FIG. 7 is a left side elevational view thereof; and,

FIG. 8 is a right side elevational view thereof.
